Elinor J. Ney of Lowell, Mass Assignor to Lowell Manuf Company
Letters Patent No. 1360 Dated Dec 18. 1860

The schedule referred to in these Letters Patent, of making part of the same To all whom it may concern:

Be it known that, Elinor J. Ney, of Lowell, in the County of Middlesex and State of Massachusetts, have originated and designed a new Pattern for Carpets or other Fabrics, of which the following is a full, clear, and exact description, reference being had to the accompanying drawings, making part of this specification.

A, in the center is a group of leaves and flowers, surrounded by a band and small blocks. B. 1, 2, 3, 4 in the corners when unrolled form a figure similar to fig A, and surrounded by similar band and blocks. Connecting the center and corners are bars D, on which rest blocks E. The figures herebefore described all rest on large diamonds composed of small regular units.
The colors employed for the different portions of the design may be varied to suit the taste and wish of the manufacturer.

What I claim as my invention and desire to secure by Letters Patent, is:

The Design or Pattern for Carpets or other Fabrics, herein set forth.
